COMBINATION DISPLAY HOLDER AND MAILING ENVELOPE FOR HANDKERCHIEFS

Doris Ann Swanson and Ruth Chantry,
Minneapolis, Minn.

Application June 16, 1954, Serial No. 31,009

Term of patent 14 years

(Cl. D80—5)

FIG. 1

FIG. 2

Fig. 1 is a top plan view of a combination display holder and mailing envelope for handkerchiefs showing our new design; and

Fig. 2 is a bottom plan view thereof.

The broken lines showing the handkerchief are for illustrative purposes only.

We claim:

The ornamental design for a combination display holder and mailing envelope for handkerchiefs, as shown and described.
